UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

MACHINE FOR ATTACHING FLAP-SECURING MEANS TO ENVELOPS.

1,131,805.

Specification of Letters Patent. Patented Mar. 16, 1915.

Original application filed July 9, 1913, Serial No. 777,998. Divided and this application filed April 6, 1914. Serial No. 329,775.

To all whom it may concern:

Be it known that I, WILLARD E. SWIFT, a citizen of the United States, residing at Worcester, in the county of Worcester and 5 Commonwealth of Massachusetts, have invented a new and useful Improvement in Machines for Attaching Flap-Securing Means to Envelops, of which the following, together with the accompanying drawings, 10 is a specification.

This application is a division of my co-pending application for patent on "Machine for attaching flap securing means to envelopes," Serial No. 777,998, filed July 9, 15 1913.

My invention relates to machines for attaching flap securing means to envelopes and more particularly to a machine for automatically attaching a button or washer to 20 the body of an envelop in such position that a string or cord carried by the flap of the envelop may be wrapped about it for the purpose of holding the flap securely closed.

The machine shown in the accompanying 25 drawings for the purpose of illustrating the present invention is provided with automatic means for reinforcing the envelop at the point at which the button is attached, this automatic means acting simultaneously 30 with the button attaching mechanism so that the attaching of the button and the reinforcement by means of a suitable fastener may be completed in a single operation.

One object of the invention is to supply 35 an improved form of guard to prevent injury to an operator by the fastener setting mechanism, automatic means being provided to move the guard out of the way as the setting mechanism operates.

Another object of the invention is to provide access to the buttons or washers during 40 their movement through their feeding mechanism for the purpose of releasing them in case they become displaced so as not 45 to feed properly.

Another object of the invention is to provide automatic means to prevent injury to an operator by the button feeding mechanism while the operator is adjusting the 50 positions of the buttons which have been displaced so as not to feed properly.

Another object of the invention is to provide an improved form of gravity tube

through which the buttons may descend during their movement toward the fastener setting mechanism, the tube being so constructed as to be easily removable from the machine but also so as to be held securely in position while in use.

Other objects and advantages will appear from the following description taken in connection with the accompanying drawings, in which—

Figure 1 is a side elevation of a machine constructed in accordance with my invention; Fig. 2 is a plan view of a portion of the machine on the line 2—2 of Fig. 1; Fig. 3 is a side elevation, the lower portion thereof being in section on the line 3—3 of Fig. 2; Fig. 4 is a plan view showing the arrangement of the driving mechanism of the machine; Fig. 5 is a front view of the lower end of the button feeding tube together with adjacent portions of the machine; Fig. 6 is a side view showing the construction which permits access to the buttons in the button tube and also showing the automatic means for protecting an operator from injury while adjusting the positions of the buttons within their tube; Fig. 7 is a view of an envelop after a button and a reinforcing tab have been attached thereto by the machine; Fig. 8 is an enlarged sectional view of the attached button and tab on the line 8—8 of Fig. 7; and Fig. 9 is a detail sectional view of the lower end of the upper set.

Like reference characters refer to identical parts in the different figures.

In the form of the invention shown in the drawings, the frame 1 supports the various operative parts of the machine in suitable positions for proper cooperation. A common main driving shaft 2, by which the moving parts of the machine are operated, is driven by a driving wheel 3 through a one-revolution clutch 4 of any desired construction. Inasmuch as this clutch forms no part of the present invention, it is indicated diagrammatically in the drawings and no description thereof is deemed necessary. The clutch is controlled by a lever 5 operated by a treadle 6 and a spring 7.

The form of machine shown is designed to secure the buttons and reinforcing tabs to the envelopes by means of fasteners in the

form of eyelets. The eyelet setting mechanism includes a removable lower die or anvil 8 secured by a set screw 9 in the upper face of the forward end of a horizontal supporting extension 10 of the frame 1. An eyelet set 11 in alignment with the die 8 is carried to and from the die by a vertically reciprocatory plunger 12 moving in vertical ways 13 formed at the forward end of a horizontal extension 14 of the frame 1. The plunger 12 is supported from a fixed pivot 15 by means of a toggle-joint composed of the links 16 and 17, the toggle-joint being driven by a rod 18 pivotally attached at its forward end to the knee of the toggle-joint and at its rear end to one arm 19 of a bell crank supported by a pivot 20 carried by the frame 1. The other arm 21 of the bell crank is pivotally connected at its free end to the upper end of a driving rod 22, the lower end of the driving rod 22 being actuated by a crank pin 23 on the face of a crank plate 24 secured at the inner free end of the driving shaft 2. It is obvious that, as the driving shaft 2 rotates, the set 11 will be reciprocated toward and from the die 8 by the connecting mechanism described so as to set and properly position an eyelet. The driving rod 22 includes a yieldable joint 25 to prevent injury to the machine in case the full setting motion of the set 11 is prevented by a broken or deformed eyelet, or otherwise. Eyelets are fed automatically to the setting mechanism through an eyelet chute 26 supported by a fixed pivot 27 so that its lower end may move into and out of the path of the set 11 as the set reciprocates. The set 11 is provided with the usual form of spring pressed picker finger 28, as shown in Fig. 9, for picking the lowermost eyelet from the chute 26 as the set descends, the finger being arranged to engage the eyelet frictionally and prevent its dropping off after the lower end of the chute has been retracted.

The die 8 and the forward end of its horizontal support 10 are surrounded by the guard 29, this guard serving also as a guide for directing an envelop into proper position between the die and the set to receive an eyelet. Fig. 7 shows an envelop 30 with an eyelet 31 after the eyelet has been set in proper position in the envelop. The guard 29 is pointed at its forward end and its walls 55 diverge rearwardly to surround the die 8 and the forward end of the support 10. An envelop to receive an eyelet is placed with its flap 32 below the guard and with the pointed end of the guard in the opening of the envelop. The envelop is then moved toward the machine until its upper face reaches the proper position under the set. As shown in Fig. 3, the guard 29 extends in its normal position above the die 8 so as to prevent the die 8 from interfering with the

motion of the envelop into fastener receiving position.

The guard 29 is provided with a pair of rearwardly extending projections 33 supported at their rear ends upon fixed pivots 34. A lever 35 carried by the pivot 36 has a slot 37 at its forward end which receives a pin 38 projecting from the side of the guard 29 so as to determine the position of the guard about its pivots 34. A pin 39 upon the rear end of the lever 35 enters a slot 40 in the forward end of the lever 41, the lever 41 being supported by a pivot 42. The position of the lever 41 is determined by a connecting rod 43 attached at its upper end to an arm 44 of the main bell crank. When the machine is at rest and the arm 44 of the bell crank is in its normal position as shown in Fig. 1, the connecting rod 43 is raised to bring the upper end of the slot 40 against the pin 39, the guard 29 being thus held in its elevated or normal position. After the machine is started, the connecting rod 43 descends and, when the lower end of the slot 40 reaches the pin 39, the guard 29 is depressed about its supporting pivots 34 so that the envelop may drop onto the anvil or die 8 to receive the eyelet. The guard 29 has an opening 45 between the die 8 and the set 11 so that it may drop without striking the die.

The buttons or washers to be secured to the envelops are dumped into a hopper 46 and are fed from this hopper into a button tube 47 by any suitable agitating mechanism actuated by an arm 48 connected to the arm 19 of the main bell crank by a connecting rod 49. The buttons descend by gravity through the button tube 47 until the lowermost button rests upon the end of a slide 50, the lower end of the tube being separated from the shelf 51 to provide space for this slide. The slide 50 is carried by one arm 52 of a bell crank, the other arm 53 of which is actuated by a connecting rod 54 driven from a cam 55 through a bell crank including the arms 56 and 57, an antifriction roller 58 carried by the arm 57 being held in contact with the periphery of the cam 55 by the spring 59. The shape of the cam 55 is such as to allow the spring 59 to move the slide 50 so as to carry the lowermost button or washer into register with the die 8 and set 11 and to hold the button in such position until it has been entered by the spring finger 28. The cam 55 then retracts the slide 50 from the path of the set 11 so that the set may descend with the washer and with the eyelet which it has previously obtained from the chute 26. While the slide 50 is feeding the lowermost button, the remainder of the stack of buttons within the tube 47 is supported by the upper face of the slide as it moves below the tube and, when the slide has been returned to its normal position, the next button will drop into its seat.

in the end of the slide and, therefore, into position to be fed upon the next forward motion of the slide.

The lower end of the button tube 47 fits into a vertical opening in the frame of the machine, a flange 60 upon the tube resting against the frame to support the tube in proper position, with its lower end just clearing the upper face of the slide 50. The flange 60 is wide enough to engage a recess or slot 61 in the frame of the machine, except that at one side the flange is reduced or cut away so that, when the tube is rotated horizontally to bring this reduced portion of the flange opposite the recess 61, it will clear the frame to allow the tube to be raised vertically and removed from the machine. The shelf 51 has an opening 62 immediately below the button tube 47 so that, in case the buttons become caught in the tube so as not to descend properly, the operator may reach them with his finger to start them again. This opening 62 is closed by a plate or closure 63 suspended by a pivot 64. The rear end of the plate 63 carries an extension reaching beyond the pivot 64 and below a second opening 65 in the shelf 51. It is impossible for an operator to reach the buttons within the tube 47 without first lowering the forward end of the plate 63 away from the opening 62. This motion of the plate raises the extension at its rear end through the opening 65 and into the path of the arm 52 which carries the slide 50. The extension, therefore, serves as a guard or protector to prevent motion of the slide 50 so as to cause injury to an operator while adjusting the stack of buttons within the tube 47. The plate 63 is held in its normal position by a spring 66.

The reinforcing tabs are fed into the machine in the form of a continuous strip or tape 67, of paper or other suitable material, carried upon a reel 68 pivotally supported at the rear of the machine. After leaving the reel 68, the tape 67 passes through a guideway 69 in the frame of the machine and then between a friction feed roll 70 and a presser roll 71. The shaft 72 of the feed roll 70 carries a driven gear wheel 73 which is in mesh with a driving gear wheel 74 rotatable upon the pivot 42. A ratchet 75 secured to one face of the driving gear wheel 74 is actuated by a pawl 76 pivotally attached to the lever 41. As the lever 41 moves, therefore, the feed roll 70 will be rotated to feed the tape 67 toward the die 8. The shaft of the presser roll 71 is journaled in blocks 77 mounted in guideways 78 formed in the frame of the machine. The blocks 77 are pressed yieldingly toward the feed roll 70 by springs 79, the force of the springs being adjustable by screws 80. The tape 67 is, therefore, held yieldingly against the feed roll 70, the yielding pressure of the

presser roll 71 being adjustable at will. The connection between the connecting rod 43 and the arm 41 of the main bell crank is adjustable to and, from the pivot 20 of the bell crank so that the angle of movement of the lever 41 and its position at each end of its path may be adjusted to cause the pawl 76 to engage properly with the teeth of the ratchet 75.

After leaving the feed roll 70, the tape 67 passes through a guide tube 81 pivoted at its rear end to the sides of the support 10. The forward end of this guide tube 81 is held in a recess formed between a shelf 82 and a cutter or knife 83 carried by the guard 29, the tube 81 moving about its pivotal support with the guard 29. The tape 67 passes from the tube 81 through an opening between the forward portions of the shelf 82 and the knife 83, this shelf and knife serving to guide the forward end of the tape into a position just above the die 8 and just below the position of the upper face of an envelop when placed in the machine to receive a fastener. A second cutter or knife 84 is secured to the support 10 immediately behind the die 8 and the cutter 83 is secured adjustably to the guard 29 by screws 85 so that it may be made to register properly with the lower cutter 84.

The relation of the parts of the machine is such that, as the set 11 descends with an eyelet and a button upon its picking finger 28, the guard 29 will drop just sufficiently to allow the lower end of the picking finger 28 to press against the die 8 with the envelop and the forward end of the tape 67 between them. The lower end of the slot 40 will then engage the pin 39 to force the cutter 83 to descend farther past the cutting edge of the cutter 84 so as to sever a tab from the forward end of the tape. The tab is, therefore, not severed until it is held firmly in position by the picking finger 28 and the die 8. The set 11 then continues to descend so as to set the eyelet, thus securing the button 86 and the severed reinforcing tab 87 upon opposite sides of the upper face of the envelop, as shown in Figs. 7 and 8. The support 10 carries a stop or gage 88 to determine the proper position of the envelop upon its supporting guard 29 so that the button 86 and tab 87 may be secured to the envelop in convenient position to receive the free end of the cord 89 carried by the flap 32.

As already suggested, it may be desired at times to set an eyelet in a shipping tag, or other article, and without any button or washer, the reinforcing tab being supplied, however, to reinforce the article at the point where the eyelet is inserted. When the machine is used for this purpose, no buttons are supplied to the hopper 46, the hopper and the button tube 47 being left

empty, or the button tube 47 may be removed from the machine if desired. The operation of the machine is otherwise unchanged.

- While I have shown and described the details of one form of my invention, I do not wish to be limited to such details as changes may be made without departing from the spirit of the invention; but
- 10. Having described my invention, what I claim as new and desire to secure by Letters Patent is:—

1. In a fastener setting machine, a set, an anvil, a support for the anvil, and a guard 15 surrounding the anvil and its support, the guard being movable toward and from the anvil and being divergent from its forward end to enter the opening of an envelop and guide the envelop toward a position around 20 the anvil and its support to receive a fastener.

2. In a fastener setting machine, means for feeding a button to the fastener setting mechanism, the feeding means including a 25 button tube rotatable in an opening in a support, and a flange on the button tube for engagement with a recess to retain the tube in operative position, the flange being reduced at one side to allow it to be disengaged from the recess by rotating the tube.

3. In a fastener setting machine, fastener setting mechanism, a button tube, button feeding means movable past the lower end of the tube, a shelf below the feeding means, 35 the shelf having an opening under the tube to permit access to buttons within the tube, a removable closure for the opening, and a

protector actuated by the closure to prevent operation of the button feeding means while the closure is removed from the opening.

4. In a fastener setting machine, fastener setting mechanism, a button tube, button feeding means movable past the lower end of the tube, a shelf below the feeding means, the shelf having an opening under the tube 45 to permit access to buttons within the tube, and a pivoted closure for the opening, the closure carrying an extension movable into the path of the feeding means as the closure is removed from the opening.

5. In a fastener setting machine, fastener setting mechanism, a button tube, button feeding means movable past the lower end of the tube, a shelf below the feeding means, the shelf having an opening under the tube 55 to permit access to buttons within the tube, and means including a closure for said opening for preventing operation of the button feeding means while the closure is removed from the opening.

6. In a fastener setting machine, fastener setting mechanism, a button tube, there being an opening to permit access to buttons within the tube, button feeding mechanism movable past said opening, and means including a closure for said opening for preventing operation of the button feeding means while the closure is removed from the opening.

Dated this first day of April, 1914.
